G. C. CHERBONNIER.
CAR DOOR OPERATING MECHANISM.
APPLICATION FILED OCT. 9, 1911.

1,084,728.

Patented Jan. 20, 1914.

UNITED STATES PATENT OFFICE.

GEORGE CASE CHERBONNIER, OF FERGUSON, MISSOURI, ASSIGNOR TO AMERICAN CAR AND FOUNDEY COMPANY, OF ST. LOUIS, MISSOURI, A CORPORATION OF NEW JERSEY.

CAR-DOOR-OPERATING MECHANISM.

1,084,728.

Specification of Letters Patent. Patented Jan. 20, 1914.

Application filed October 9, 1911. Serial No. 653,758.

To all whom it may concern:

Be it known that I, GEORGE CASE CHERBONNIER, a citizen of the United States, residing at Ferguson, Missouri, have invented 5 a certain new and useful Improvement in Car-Door-Operating Mechanism, of which the following is a full, clear, and exact description, such as will enable others skilled in the art to which it appertains to make 10 and use the same, reference being had to the accompanying drawings, forming part of this specification, in which—

Figure 1 is a top plan view of a portion of a car provided with my improved door 15 operating mechanism. Fig. 2 is a side elevational view of the same. Fig. 3 is a sectional view on line 3—3 of Fig. 2. Fig. 4 is a perspective view of one of the latching devices.

This invention relates to a new and useful 20 improvement in door operating mechanism for railway cars particularly of the dump or hopper bottom type, and has for its object improvements in mechanisms of this character in general and particularly of that type disclosed in United States Patent No. 905,123 granted to me January 18, 1908.

Referring to the drawings: 1 indicates one 25 of the center sill members of the car, 2 the floor sheet, 3 the side sill and 4 the side wall of the car. The floor sheet is provided with openings through which the contents of the car are intended to be discharged, said openings being closed by doors 5, one of which 30 is shown in the drawings. The door 5 is hinged in a suitable manner to the center sill of the car and extends out to the side sill under which the free edge of the door is arranged, when closed, as shown. The door 35 may be reinforced by strengthening angles 40 in any appropriate manner and fixed to its free edge are bracket lugs or housings 6, constituting pivotal supports for the latching devices 7. These locks, as shown in detail 45 in Fig. 4, are each provided on one side with a lateral extension 7^a which coöperates with a projection 6^a on the bracket lug 6 whereby the lock is prevented from swinging outwardly too far, but is permitted to 50 swing inwardly as far as is necessary. Each lock has an inclined wall 7^b, the outer surface of which is designed to bear against the winding shaft 8 as the door is raised to its 55 closed position, thus causing the lock to swing inwardly until the lower curved edge

7^c thereof is located above the shaft whereupon the lock is drawn outwardly by the winding chain, thereby locating the wall 7^c above the shaft, as shown in Fig. 3. This wall 7^c is slightly eccentric, the outer edge 60 thereof being closer to the axis of movement of the lock than is the inner edge of said wall. In this manner, as the shaft 8 continues to rotate in raising the door, it will engage and tend to wedge the lock in place 65 swinging the lock outwardly until a web 7^d contacts with the shaft 8. The eccentricity of the bearing faces 7^e is very slight and only sufficient to insure contact of the latching members with the winding shaft in cases 70 where the sides of the door are not drawn up equally.

Each door is provided with a pair of locks or latching devices and the members of each pair are connected by a bar or rail 12, the 75 ends of which are preferably attached in any suitable manner to downwardly extending walls or flanges 7^e, the same being formed integral with the lower portions of said locks. This rail or bar performs the 80 function of an equalizing bar, and attached to an eye bolt 13 at the center of the bar is one end of a chain or cable 11, the other end of which is attached to the winding shaft 8. As the winding shaft 8 is operated to wind 85 the chain 11 thereupon, the free edge of the door is drawn upward past the winding shaft, and during this movement the inclined faces 7^b of the locks or latching devices engage against the winding shaft, and said locks to pass said shaft must necessarily move inward a short distance. As soon as the lower ends of the latching devices pass 90 above the winding shaft, said latching devices will be drawn outward by the pull of 95 the chain connected to the bar 12, and thus the bearing faces of the walls 7^c will be drawn into engagement with the winding shaft, and the locks will hold the door in 100 closed position. The winding chain or cable 11 is preferably attached to the center of the bar 12 and thus said bar becomes an 105 equalizer to distribute the strain equally between the two locks in raising the door to its closed position.

It will be noted that in my former patent parts of the locks engaged against the winding chains and were thereby moved rearwardly so as to pass the winding shaft, but in my present construction the latches are 110

moved inward as the faces 7^b engage the winding shaft during the closing movement of the door.

It will be noted that the forward portion 5 of the housings 6 extends over the upper end of the latch, and thus material such as sand, crushed rock, coal and other foreign substances are prevented from dropping in behind the upper ends of the latches, and 10 thereby interfering with the swinging movements of said latches.

It will be readily understood that minor 15 changes in the size, form and construction of the various parts of my improved door operating mechanism may be made and substituted for those herein shown and described without departing from the spirit of my invention, the scope of which is set forth in the appended claims.

20 What I claim is:

1. In a door operating mechanism the combination, of a door, a winding shaft, pivoted locking members carried by the free edge of the door for coöperating with the 25 winding shaft when the door is in its closed position, said locking members being connected together and a flexible member attached to said shaft and to the connection between said locking members.

30 2. In a door operating mechanism the combination, of a door, a winding shaft, door locking devices pivotally mounted on the free edge of the door and designed to co-operate with the winding shaft when the 35 door is in its closed position, an equalizing bar connecting said devices and a flexible member attached to said winding shaft and said equalizing bar.

3. In a door operating mechanism the 40 combination, of a door, a winding shaft, latches pivotally mounted on the free edge of the door for engaging the winding shaft to lock the door in its closed position, which latches bear against the winding shaft and 45 are moved inwardly to pass said shaft during the closing movement of the door, a rigid connection between the lower portions of the gravity latches and a flexible member between said rigid connection and the winding shaft.

4. In a door operating mechanism, the combination with a door, of a winding shaft, latches pivotally connected to the free edge of the door and adapted to coöperate with 55 the winding shaft for supporting the door in its closed position, which latches are provided with eccentric shaft engaging faces, a connection between said latches, and a

flexible connection between the winding shaft and the connection between said latches.

5. In a door operating mechanism, the combination with a door, of a winding shaft, door locking devices pivotally mounted on the free edge of the door and adapted to 65 engage the winding shaft to hold the door in closed position, means for limiting the outward swing of said locking devices, an equalizing bar connecting said devices, and a flexible member attached to the winding 70 shaft and said equalizing bar.

6. A door operating mechanism comprising a door, a winding shaft and connections for raising the door to its closed position, including a pair of pivotally mounted 75 connected locking devices adapted to coöperate with the winding shaft to hold the door in closed position, which connected locking devices are drawn into engagement with the winding shaft by parts of the door raising 80 means.

7. In a car door operating mechanism, the combination with a door, of a winding shaft and connections for raising the door to its closed position, including a pair of connected 85 locking members pivotally mounted on the free edge of the door and adapted to engage the winding shaft to hold the door in closed position.

8. In a car door operating mechanism, the 90 combination with a door, of a winding shaft and connections for raising the door to its closed position, including a pair of connected locking members pivotally mounted on the free edge of the door and adapted to 95 engage the winding shaft to hold the door in closed position, which locking members are provided with curved shaft engaging faces.

9. In a car door operating mechanism, the 100 combination with a door, of a winding shaft and connections for raising the door to its closed position, including a pair of connected locking members pivotally mounted on the free edge of the door and adapted to 105 engage the winding shaft to hold the door in closed position, which locking members are provided with eccentric shaft engaging faces.

In testimony whereof I hereunto affix my 110 signature in the presence of two witnesses, this 26th day of September, 1911.

GEORGE CASE CHERBONNIER.

Witnesses:
